(57) **ABSTRACT**

A carton. The carton may include a floor panel; a plurality of side panels extending about a periphery of the floor panel, a front tab formed at an upper edge of a front side panel, upper side flaps extending from upper edges of a first end side panel and a second end side panel, and wherein each flap includes a side receiving slot; foldable corner gussets extending between adjacent side panels, wherein the floor panel, side panels, and foldable corner gussets are configurable to form a compartment region; a hingeable lid, including: a lid panel, a front edge flap, a side tab formed on each opposing side edge of the lid panel, and a front receiving slot formed in the front edge flap, wherein the lid panel is configured to cover the compartment region when in a closed position; and wherein the front tab of the front side panel is configured such that when the hingeable lid is in the closed position, the front tab aligns with the front receiving slot and is receivable therein and each side tab aligns with its respective side receiving slot and are receivable therein.

CLOSEABLE CARTON

RELATED APPLICATIONS

This application is a continuation patent application of U.S. patent application Ser. No. 29/727,102, filed Mar. 9, 2020, the disclosure of which is incorporated herein by reference in its entirety.

TECHNICAL FIELD

The subject matter of the invention relates generally to carry-out food cartons, and more particularly to a closeable carton with a hinged lid and webbed corners and method of using same.

BACKGROUND

Various products are known to be purchased by consumers which require a carton for ease of transport. For example, in the food and grocery industry it is common to place food items in individual carry-out food cartons. There may be certain drawbacks to commonly used carry-out food cartons. For example, cardboard-, paper-, and/or paperboard-based cartons may not be suitable for holding wet foods reliably without leaking. Further, often carry-out food cartons are not designed for reliable stacking.

SUMMARY

In one embodiment, a closeable carton is provided. The closeable carton may include a floor panel and a plurality of side panels extending about a periphery of the floor panel. The plurality of side panels may include a front side panel, an opposing rear side panel, a first end panel, and an opposing second end panel, wherein the front side panel may include a front tab formed at an upper edge thereof, and wherein the first end panel and the second end panel each may include an upper side flap extending from an upper edge thereof, and wherein each flap may include a side receiving slot formed therein. The closeable carton may further include foldable corner gussets extending between adjacent side panels, wherein the floor panel, side panels, and foldable corner gussets are configurable to form a compartment region. The closeable carton may further include a hingeable lid, that may include a lid panel, a front edge flap extending from a front edge of the lid panel, a side tab formed on each opposing side edge of the lid panel, and a front receiving slot formed in the front edge flap, wherein the lid panel may be configured to cover the compartment region when in a closed position, and wherein the front tab of the front side panel is sized, shaped, and positioned such that when the hingeable lid is in the closed position, the front tab aligns with the front receiving slot and is receivable therein and each side tab aligns with its respective side receiving slot and are receivable therein. Adjacent side panels and end panels may be coupled together via the foldable corner gussets. The front receiving slot may be configured such that when the hingeable lid is in the closed position the front receiving slot is engageable with the front tab to secure the hingeable lid in the closed position. Each side receiving slot may be configured such that when the hingeable lid is in the closed position each side receiving slot is engageable with its respective side tab. Each side tab may be formed proximate to opposing side edges of the lid panel. The hingeable lid panel may be hingeably coupled to a top edge of the rear side panel via a fold line. The flap of each of the first end

2

panel and the second end panel and the front edge flap of the hingeable lid may be configured to fold inward. The front edge flap of the hingeable lid may be configured to tuck behind the front side panel when the hingeable lid is in the closed position. The foldable corner gussets may each include a first side portion and an adjacent second side portion, wherein the first side portion and the second side portions intersect at a fold line therebetween. The foldable corner gussets may be configured to be folded along their respective fold lines such that opposing faces of adjacent first and second side portions come in contact with one another. The folded foldable corner gussets may be configured to be further folded such that an interior or exterior facing surface of one of the first or second side portions comes in contact with an interior or exterior surface of its corresponding adjacent side panel. An adhesive or heat sealable coating may hold the folded adjacent first and second side portions in contact with one another. An adhesive or heat sealable coating may hold the folded corner gusset in contact with the interior or exterior surface of its corresponding adjacent side panel. The carton may further include one or more vent flaps formed in one or more of the plurality of side panels. The one or more vent flaps may be formed in at least one of the front side panel and/or the rear side panel. The one or more vent flaps may be defined by a perforation or score line about at least a portion of its periphery, wherein the one or more vent flaps may be one of partially or fully removable.

In another embodiment, a method of using a closeable carton is provided. The method may include providing a closeable carton; folding each of the upper side flaps and the front edge flap inward; folding the hingeable lid to the closed position; tucking the front edge flap behind the front side panel; and engaging the front tab of the front side panel with the front receiving slot of the hingeable lid and/or one or more of the side tabs of the hinged carton lid with its respective one or more of the side receiving slots of the upper edge flaps. The carton may include one or more vent flaps formed in one or more of the plurality of side panels. The method may further include partially or fully removing one or more of the one or more vent flaps.

BRIEF DESCRIPTION OF THE DRAWINGS

Having thus described the subject matter of the invention in general terms, reference will now be made to the accompanying Drawings, which are not necessarily drawn to scale, and wherein:

FIG. 1 is a perspective view of an example closeable carton, in accordance with an embodiment of the invention;

FIG. 2 is a front elevation view of the closeable carton of FIG. 1, in accordance with an embodiment of the invention;

FIG. 3 is a rear elevation view of the closeable carton of FIG. 1, in accordance with an embodiment of the invention;

FIG. 4 is a side elevation view of the closeable carton of FIG. 1, in accordance with an embodiment of the invention;

FIG. 5 is a top plan view of the closeable carton of FIG. 1, in accordance with an embodiment of the invention;

FIG. 6 is a bottom plan view of the closeable carton of FIG. 1, in accordance with an embodiment of the invention;

FIG. 7 is another perspective view of the closeable carton of FIG. 1 shown in an example open configuration, in accordance with an embodiment of the invention;

FIG. 8 is a front elevation view of the closeable carton of FIG. 7, in accordance with an embodiment of the invention;

FIG. 9 is a rear elevation view of the closeable carton of FIG. 7, in accordance with an embodiment of the invention;

FIG. 10 is a side elevation view of the closeable carton of FIG. 7, in accordance with an embodiment of the invention;

FIG. 11 is a top plan view of the closeable carton of FIG. 7, in accordance with an embodiment of the invention;

FIG. 12 is a bottom plan view of the closeable carton of FIG. 7, in accordance with an embodiment of the invention;

FIG. 13 is a top plane view of the of the closeable carton of FIG. 1 shown in an example flat unfolded configuration, in accordance with an embodiment of the invention;

FIG. 14 is another perspective view of the closeable carton of FIG. 1 showing an example alternate configuration, in accordance with an embodiment of the invention;

FIG. 15 is another perspective view of the closeable carton of FIG. 14 shown in an example open configuration, in accordance with an embodiment of the invention; and

FIG. 16 illustrates a flow diagram of an example of a method of using the closeable carton, in accordance with an embodiment of the invention.

DETAILED DESCRIPTION

The subject matter of the invention now will be described more fully hereinafter with reference to the accompanying Drawings, in which some, but not all embodiments of the subject matter of the invention are shown. Like numbers refer to like elements throughout. The subject matter of the invention may be embodied in many different forms and should not be construed as limited to the embodiments set forth herein; rather, these embodiments are provided so that this disclosure will satisfy applicable legal requirements. Indeed, many modifications and other embodiments of the subject matter of the invention set forth herein will come to mind to one skilled in the art to which the subject matter of the invention pertains having the benefit of the teachings presented in the foregoing descriptions and the associated Drawings. Therefore, it is to be understood that the subject matter of the invention is not to be limited to the specific embodiments disclosed and that modifications and other embodiments are intended to be included within the scope of the appended claims.

In some embodiments, the subject matter of the invention provides a closeable carton with a hinged lid and webbed corners and method of using same. In one example, the subject closeable carton includes a carton body and a hinged carton lid, and wherein the carton body includes a solid floor panel and webbed corners. Accordingly, the subject carton may be used as a disposable food carry-out (or take-out) carton that is suitable for holding wet foods reliably for some useful period of time.

In some embodiments, the carton body and/or hinged carton lid of the subject carton may include various tabs and slots that may be engaged for holding shut the hinged carton lid to the carton body.

In some embodiments, the subject carton includes a substantially flat hinged carton lid that allows for easy stacking of multiple of the subject cartons.

In some embodiments, the webbed corners of the subject carton may be held by glue or other adhesive.

In some embodiments, the webbed corners of the subject carton may be held by heat-sealable coatings, wherein the carton body may be folded into its assembled state and the corner flaps folded and heat sealed to an inside or outside surface of the assembled carton body without adding any glue, thereby providing a fully compostable carton.

Additionally, a method of using the subject carton is provided.

In some embodiments, the carton body and/or the hinged carton lid of the subject carton may include a tamper-evident feature that may be used to indicate a “secure” condition of the carton and wherein the tamper-evident feature may be, for example, a perforated tear line, a tear-away strip, and/or the like.

Referring now to FIGS. 1 through 15, show various views and embodiments of an example of the subject carton 100 that may have a hinged lid 130, webbed corners 118, and a solid carton bottom. The carton 100 may be used, for example, as a disposable food carry-out (or take-out) carton that is openable and closable.

The carton 100 may include a carton body 110 and a hinged carton lid 130. The carton body 110 may further include a floor panel 112, two opposing side panels 114 (e.g., a front side panel 114a and a rear side panel 114b), and two opposing end panels 116. The ends of the side panels 114 and the end panels 116 may be coupled via webbed corners 118. The webbed corners 118 may be, for example, a webbed corner inside glue design, wherein the webbed corners 118 may be adhered to an interior surface of their adjacent end panel 116 or side panel 114 (as shown, for example, in FIG. 7). Alternatively, the webbed corners 118 may be, for example, a webbed corner outside glue design, wherein the webbed corners 118 may be adhered to an exterior surface of their adjacent end panel 116 or side panel 114 (as shown, for example, in FIG. 14). The webbed corners 118 may be secured, for example, via an adhesive, thermal bonding, or any other suitable technique or mechanism. Each of the end panels 116 may include an upper edge flap 120. Each of the upper edge flaps 120 may include a side receiving slot 122. Further, a front locking tab 124 may be provided at the top edge of the front side panel 114a.

The hinged carton lid 130 may be a substantially flat hinged carton lid. The hinged carton lid 130 may include a lid panel 132 that may be hingeably coupled to the top edge of the rear side panel 114b of the carton body 110 via a fold line 134. A front edge flap 136 may be provided at the front edge of the lid panel 132. The front edge flap 136 of the lid panel 132 may include a front edge receiving slot 138. Further, a side locking tab 140 may be provided at each opposing end of lid panel 132.

The front edge receiving slot 138 of the hinged carton lid 130 may be designed to receive and hold the front locking tab 124 of the carton body 110. The side receiving slots 122 of the carton body 110 may be designed to receive and hold the side locking tabs 140 of the hinged carton lid 130. Further, the rear side panel 114b may include one or more vent flaps 142 (as shown, for example, in FIGS. 3, 7, 9, 13, 15).

The carton body 110 and the hinged carton lid 130 of the carton 100 may be formed of any lightweight, rigid or semi-rigid material that is suitable for holding and/or transporting, for example, a quantity of food and that is also suitable for disposing of after use. For example, the carton 100 may be formed of corrugated cardboard, paper, paperboard, post-consumer paperboard (i.e., recycled materials), biodegradable materials (e.g., sugarcane and paper), polystyrene foam (e.g., Styrofoam), plastic, molded fiber, and the like.

In operation, a user may fold the hinged carton lid 130 to a closed position and tucks the front edge flap 136 of the lid panel 132 behind the front side panel 114a of the carton body 110. Then, the user may engage the front locking tab 124 of the carton body 110 with the front edge receiving slot 138 of the hinged carton lid 130. Then, the user may engage

the side locking tabs 140 of the hinged carton lid 130 with the side receiving slots 122 of the carton body 110.

One benefit of the presently disclosed carton 100 is that the carton body 110 has a solid floor panel 112 and that the carton body 110 is formed using the webbed corners 118 to form a disposable food carry-out (or take-out) carton that is suitable for holding wet foods reliably for some useful period of time without leaking.

For example, to form the carton body 110, the webbed corners 118 may be folded inward. Then, glue or other adhesive may be applied inside the fold such that facing surfaces of the webbed corners 118 are adhered or otherwise bonded together. In another example, a heat-sealable coating may be applied to the surfaces inside the fold of the webbed corners 118. Then, for each webbed corner 118, once the facing surfaces of the webbed corner 118 are folded into contact with one another, heat may be applied to the folded area and causing the heat-sealable coating to bond the facing surfaces of the webbed corner 118 together. Once the facing surfaces of the webbed corners 118 are adhered or otherwise bonded together, the folded webbed corners 118 may then be folded over in contact with an inside surface of its adjacent end panel 116 or side panel 114 and adhered or otherwise bonded thereto. Glue or other adhesive may be used to adhere or otherwise bond folded webbed corners 118 to the inside surface its adjacent end panel 116 or side panel 114. In another example, a heat-sealable coating may be applied to all or select surfaces of the interior facing surface of the carton body 110, and once the webbed corner 118 are folded into contact with the inside surface its adjacent end panel 116 or side panel 114, heat may be applied to the area and causing the heat-sealable coating to bond the webbed corner 118 thereto.

In another embodiment, to form the carton body 110, the webbed corners 118 may be folded outward. Then, glue or other adhesive may be applied inside the fold such that facing surfaces of the webbed corners 118 are adhered or otherwise bonded together. In another example, a heat-sealable coating may be applied to the surfaces inside the fold of the webbed corners 118. Then, for each webbed corner 118, once the facing surfaces of the webbed corner 118 are folded into contact with one another, heat may be applied to the folded area and causing the heat-sealable coating to bond the facing surfaces of the webbed corner 118 together. Once the facing surfaces of the webbed corners 118 are adhered or otherwise bonded together, the folded webbed corners 118 may then be folded over in contact with an outside surface of its adjacent end panel 116 or side panel 114 and adhered or otherwise bonded thereto (for example as shown in FIGS. 14 an 15). Glue or other adhesive may be used to adhere or otherwise bond folded webbed corners 118 to the outside surface of its adjacent end panel 116 or side panel 114. In another example, a heat-sealable coating may be applied to all or select surfaces of the exterior facing surface of the carton body 110, and once the webbed corner 118 are folded into contact with the exterior surface of its adjacent end panel 116 or side panel 114, heat may be applied to the area and causing the heat-sealable coating to bond the webbed corner 118 thereto.

Another benefit of the presently disclosed carton 100 is that the substantially flat hinged carton lid 130 allows for easy stacking of multiple of the cartons 100.

Referring now to FIG. 16 is a flow diagram of an example of a method 200 of using the presently disclosed carton 100.

The method 200 may include, but is not limited to, the following steps, and not necessarily in the following order.

At a step 210, the carton 100 is provided.

At a step 215, a user may fold the upper edge flaps 120 inward.

At a step 220, a user may fold the hinged carton lid 130 to the closed position and tuck the front edge flap 136 of the lid panel 132 into the front side panel 114a of the carton body 110.

At a step 225, the user may engage the front locking tab 124 of the carton body 110 with the front edge receiving slot 138 of the hinged carton lid 130.

At a step 230, the user may engage one or both of the side locking tabs 140 of the hinged carton lid 130 with one or more of the side receiving slots 122 of the upper edge flaps 120 of the carton body 110.

In other embodiments, the carton body 110 and/or the hinged carton lid 130 of the presently disclosed carton 100 may include a tamper-evident feature (not shown) that may be used to indicate a "secure" condition of the carton 100. For example, the tamper-evident feature may be a perforated tear line, a tear-away strip, and/or the like. In one example, when the perforated tear line or tear-away strip is fully intact, the carton 100 is in the "secure" condition. By contrast, when the perforated tear line or tear-away strip is shown to be compromised, the carton 100 is in a "tamper-evident" condition.

Following long-standing patent law convention, the terms "a," "an," and "the" refer to "one or more" when used in this application, including the claims. Thus, for example, reference to "a subject" includes a plurality of subjects, unless the context clearly is to the contrary (e.g., a plurality of subjects), and so forth.

Throughout this specification and the claims, the terms "comprise," "comprises," and "comprising" are used in a non-exclusive sense, except where the context requires otherwise. Likewise, the term "include" and its grammatical variants are intended to be non-limiting, such that recitation of items in a list is not to the exclusion of other like items that can be substituted or added to the listed items.

For the purposes of this specification and appended claims, unless otherwise indicated, all numbers expressing amounts, sizes, dimensions, proportions, shapes, formulations, parameters, percentages, quantities, characteristics, and other numerical values used in the specification and claims, are to be understood as being modified in all instances by the term "about" even though the term "about" may not expressly appear with the value, amount or range. Accordingly, unless indicated to the contrary, the numerical parameters set forth in the following specification and attached claims are not and need not be exact, but may be approximate and/or larger or smaller as desired, reflecting tolerances, conversion factors, rounding off, measurement error and the like, and other factors known to those of skill in the art depending on the desired properties sought to be obtained by the presently disclosed subject matter. For example, the term "about," when referring to a value can be meant to encompass variations of, in some embodiments $\pm 100\%$, in some embodiments $\pm 50\%$, in some embodiments $\pm 20\%$, in some embodiments $\pm 10\%$, in some embodiments $\pm 5\%$, in some embodiments $\pm 1\%$, in some embodiments $\pm 0.5\%$, and in some embodiments $\pm 0.1\%$ from the specified amount, as such variations are appropriate to perform the disclosed methods or employ the disclosed compositions.

Further, the term "about" when used in connection with one or more numbers or numerical ranges, should be under-

stood to refer to all such numbers, including all numbers in a range and modifies that range by extending the boundaries above and below the numerical values set forth. The recitation of numerical ranges by endpoints includes all numbers, e.g., whole integers, including fractions thereof, subsumed within that range (for example, the recitation of 1 to 5 includes 1, 2, 3, 4, and 5, as well as fractions thereof, e.g., 1.5, 2.25, 3.75, 4.1, and the like) and any range within that range.

Although the foregoing subject matter has been described in some detail by way of illustration and example for purposes of clarity of understanding, it will be understood by those skilled in the art that certain changes and modifications can be practiced within the scope of the appended claims.

That which is claimed:

1. A carton, comprising:

a. a floor panel;

b. a plurality of side panels extending about a periphery of the floor panel, the plurality of side panels comprising a front side panel, an opposing rear side panel, a first end panel, and an opposing second end panel, wherein the front side panel comprises a single front tab formed and centered at an upper edge thereof, wherein a top edge of the front tab is substantially flush with a top edge of the front side panel, and wherein the first end panel and the second end panel each comprise an upper side flap extending from an upper edge thereof, and wherein each flap comprises a side receiving slot formed therein, and wherein each corner fold line between each side panel side edge and its adjacent foldable corner gussets are formed at a substantially 90 degree angle with respect to each fold line between each side panel and the floor panel, and wherein in a folded assembled state the side panels are configured at a substantially 90 degree angle with respect to the floor panel;

c. foldable corner gussets extending between adjacent side panels, wherein the floor panel, side panels, and foldable corner gussets are configurable to form a compartment region;

d. a hingeable lid, comprising: a lid panel, a front edge flap extending from a front edge of the lid panel, a side tab formed on each opposing side edge of the lid panel, and a single front receiving slot formed in the front edge flap, wherein the front receiving slot is disposed between a front edge of the front edge flap and the front edge of the lid panel, and wherein the lid panel is configured to cover the compartment region when in a closed position; and

wherein the front tab of the front side panel is sized, shaped, and positioned such that when the hingeable lid is in the closed position, the front tab aligns with the front receiving slot and is receivable therein and each side tab aligns with its respective side receiving slot and are receivable therein.

2. The carton of claim 1, wherein adjacent side panels and end panels are coupled together via the foldable corner gussets.

3. The carton of claim 1, wherein the front receiving slot is configured such that when the hingeable lid is in the closed position the front receiving slot is engageable with the front tab to secure the hingeable lid in the closed position.

4. The carton of claim 1, wherein each side receiving slot is configured such that when the hingeable lid is in the closed position each side receiving slot is engageable with its respective side tab.

5. The carton of claim 1, wherein each side tab is formed proximate to opposing side edges of the lid panel.

6. The carton of claim 1, wherein the hingeable lid panel is hingeably coupled to a top edge of the rear side panel via a fold line.

7. The carton of claim 1, wherein the flap of each of the first end panel and the second end panel and the front edge flap of the hingeable lid are configured to fold inward.

8. The carton of claim 1, wherein the front edge flap of the hingeable lid is configured to tuck behind the front side panel when the hingeable lid is in the closed position.

9. The carton of claim 1, wherein the foldable corner gussets each comprise a first side portion and an adjacent second side portion, wherein the first side portion and the second side portions intersect at a fold line therebetween.

10. The carton of claim 9, wherein the foldable corner gussets are configured to be folded along their respective fold lines such that opposing faces of adjacent first and second side portions come in contact with one another.

11. The carton of claim 10, wherein the folded foldable corner gussets are configured to be further folded such that an interior or exterior facing surface of one of the first or second side portions comes in contact with an interior or exterior surface of its corresponding adjacent side panel.

12. The carton of claim 11, wherein an adhesive or heat sealable coating holds the folded corner gusset in contact with the interior or exterior surface of its corresponding adjacent side panel.

13. The carton of claim 10, wherein an adhesive or heat sealable coating holds the folded adjacent first and second side portions in contact with one another.

14. The carton of claim 1, further comprising one or more vent flaps formed in one or more of the plurality of side panels.

15. The carton of claim 14, wherein the one or more vent flaps are formed in at least one of the front side panel and the rear side panel.

16. The carton of claim 14, wherein the one or more vent flaps are defined by a perforation or score line about at least a portion of its periphery, wherein the one or more vent flaps are one of partially or fully removable.

17. A method of using a carton, comprising:

a. providing a carton, comprising:

i. a floor panel;

ii. a plurality of side panels extending about a periphery of the floor panel, the plurality of side panels comprising a front side panel, an opposing rear side panel, a first end panel, and an opposing second end panel, wherein the front side panel comprises a single front tab formed and centered at an upper edge thereof, wherein a top edge of the front tab is substantially flush with a top edge of the front side panel, and wherein the first end panel and the second end panel each comprise an upper side flap extending from an upper edge thereof, and wherein each flap comprises a side receiving slot formed therein, and wherein each corner fold line between each side panel side edge and its adjacent foldable corner gussets are formed at a substantially 90 degree angle with respect to each fold line between each side panel and the floor panel, and wherein in a folded assembled state the side panels are configured at a substantially 90 degree angle with respect to the floor panel;

- iii. foldable corner gussets extending between adjacent side panels, wherein the floor panel, side panels, and foldable corner gussets are configurable to form a compartment region; and
- iv. a hingeable lid, comprising: a lid panel, a front edge flap extending from a front edge of the lid panel, a side tab formed on each opposing side edge of the lid panel, and a single front receiving slot formed in the front edge flap, wherein the front receiving slot is disposed between a front edge of the front edge flap and the front edge of the lid panel, and wherein the lid panel is configured to cover the compartment region when in a closed position, and wherein the front tab is sized, shaped, and positioned such that when the hingeable lid is in the closed position, the front tab aligns with the front receiving slot and is receivable therein and each side tab aligns with its respective side receiving slot and are receivable therein;

5

10

- b. folding each of the upper side flaps and the front edge flap inward;
- c. folding the hingeable lid to the closed position;
- d. tucking the front edge flap behind the front side panel; and
- e. engaging the front tab of the front side panel with the front receiving slot of the hingeable lid and/or one or more of the side tabs of the hinged carton lid with its respective one or more of the side receiving slots of the upper edge flaps.

18. The method of claim 17, wherein carton further comprising one or more vent flaps formed in one or more of the plurality of side panels.

19. The method of claim 18, further comprising partially or fully removing one or more of the one or more vent flaps.
